UNITED STATES PATENT OFFICE.

HENRY J. HEINZ, OF PITTSBURG, PENNSYLVANIA.

DESIGN FOR A BOTTLE.

SPECIFICATION forming part of Design No. 22,304, dated March 21, 1893.

Application filed December 5, 1892. Serial No. 454,176. Term of patent 14 years.

To all whom it may concern:

Be it known that I, HENRY J. HEINZ, of Pittsburgh, in the county of Allegheny and State of Pennsylvania, have invented a new 5 and original Design for Bottles, of which the following is a full, clear, and exact description, reference being had to the accompanying drawings, which show in Figure 1, a side elevation and in Fig. 2, a cross-section of a 10 bottle embodying my design.

The design consists in a bottle of form substantially as herein described and shown in the drawings.

In the drawings 2 represents the body of 15 the bottle which is polygonal in cross-section, and has upright surface panels 3, extending more than one-half the height of the bottle,

approximately two-thirds thereof. The upper part 4 of the bottle is tapering in the form of a short frustum of a cone, and the same is 20 also provided with surface panels, rendering its outline polygonal in cross-section corresponding to the outline of the lower portion of the bottle.

I claim—

The design for bottles substantially as herein shown and described.

In testimony whereof I have hereunto set my hand.

HENRY J. HEINZ.
